(57) **CLAIM**

The ornamental design for a tapered valve seat, as shown and described.

DESCRIPTION

FIG. 1 is a side plan view of a tapered valve seat showing our new design, the right side, left side, front side and back side being identical;

FIG. 2 is a sectional plan view taken along line 2-2 of FIG. 3 thereof;

FIG. 3 is a bottom plan view thereof;

FIG. 4 is a top plan view thereof;

FIG. 5 is a top perspective view thereof; and,

FIG. 6 is a bottom perspective view thereof.

1 Claim, 6 Drawing Sheets
